UNITED STATES PATENT OFFICE

ERNEST E. CLARK, OF KANSAS CITY, MISSOURI

INKSTAND

Application filed February 29, 1932. Serial No. 595,760.

My invention relates to improvements in ink stands. It relates particularly to ink wells of a type in which the ink is automatically fed from an ink container into and retained at a constant level in a dipping well.

One of the objects of my invention is to provide a novel ink stand of the kind described which is adapted to be disposed in a reclining operative position, in which the ink will automatically flow from the container into the dipping well, and which when not in use can be disposed in an upright position in which the ink will flow back from the dipping well into the container, thereby preventing an accumulation of sediment in the dipping well and affording always thereto a supply of fresh ink.

A further object of my invention is to provide a novel container having a relatively large filling and discharge opening to enable easy access to the interior of the container for filling or cleaning purposes.

My invention provides further a novel closure for the container opening provided with a novel dipping well adapted for use with an ordinary pen or for the filling of a fountain pen, the closure having an opening connecting the dipping well with the interior of the container, the closure also being provided with a novel air conduit connecting the dipping well with the container, whereby a constant level of ink is retained in the well.

My invention provides further novel means for releasably holding the closure in a tightly closed position on the container, and which is adapted for use for assisting in supporting the ink stand in its reclining operative position.

My invention provides further a novel closure for the dipping opening of the dipping well which, when the ink stand is moved from the reclining operative position to the upright inoperative position, will automatically move to the closed position.

My invention provides still further a novel ink stand which is simple, cheap to make, strong, durable, not likely to be easily broken or to get out of order, from which the ink is not liable to be accidentally spilled, which is efficient in its operation and from which the

ink can be used until an exceedingly small amount remains therein.

The novel features of my invention are hereinafter fully described and claimed.

In the accompanying drawing, which illustrates my invention,

Fig. 1 is a side view, partly in elevation and partly in vertical section of one form of my invention in which the closure for the container is held clamped to the container by means which also serves to assist in supporting the ink stand in the reclining operative position in which it is shown.

Fig. 2 is a side elevation of the ink stand shown in Fig. 1 disposed in the upright inoperative position.

Fig. 3 is an elevation looking at another side of the ink stand shown in Fig. 2.

Fig. 4 is a reduced longitudinal vertical sectional view of another form of my invention, in which the closure for the container has threaded connection therewith, the ink stand being shown in the reclining operative position.

Fig. 5 is a reduced end elevation of the ink stand shown in Fig. 4.

Similar characters of reference designate similar parts in the different views.

Referring to Figs. 1 to 3, 1 designates an ink container, which is of any suitable material, as metal, but preferably, as shown, of glass, and which may be of most any desired shape. In the form shown the container 1 is a cylindrical body having an opening in one end preferably of the full inner diameter of the body. The open end portion of the container 1 is provided with a peripheral gasket 2 which bears against an annular peripheral flange 3.

4 designates a closure for the open end of the container 1 consisting, preferably of glass, as shown, or of hard rubber or similar material. The rear side of the closure 4 is provided with an annular flange 5 adapted to tightly bear against the gasket 2.

The closure 4 is provided adjacent to its periphery with a dipping well 6 having at its rear end adjacent to its bottom an opening 7 communicating with the interior of the container 1.

The well has a closed top having a hole in which is fitted tightly a bushing 8 of hard rubber or other suitable material, the opening 9 therethrough serving as a dipping opening for the insertion into the well of a pen, ordinary or fountain.

Pivoted by a hinge 10 to the upper forward edge of the bushing 8 is a closure 11, which, in the closed position shown in solid lines in Fig. 1, closes the dipping opening 9, and which in the open position, shown in dotted lines in Fig. 1, rests on a forwardly and upwardly extending projection 12, which holds the closure 11 in a position such that, when the ink stand is moved from the reclining position shown in Fig. 1 to the upright position shown in Figs. 2 and 3, the closure 11 will swing by gravity to the closed position, Fig. 2.

For holding the flange 5 tightly against the gasket 2, there is provided a U shaped wire clamping member 13, the transverse portion of which engages the middle of the outer side of the closure 4.

The arms of the clamping member 13 are disposed respectively at opposite sides of the container 1 and have inwardly turned ends 14 which are respectively pivoted in eyes 15 provided respectively in the two arms 16 of a U shaped lever, the ends of the arms 16 being inwardly turned and respectively pivoted in two recesses 17 of two diametrically opposite bosses 18 forming two bearings on the periphery of the container 1.

The transverse portion of the U shaped lever is provided at opposite sides of the container 1 with two U shaped legs 19 adapted to serve as supports to hold the container 1 forwardly and downwardly inclined when the container is in the operative reclining position, shown in Fig. 1. Between the legs 19 the lever has an arcuate portion 20 the concave side of which is adapted to embrace and support the under side of the container 1.

To permit air to enter the container 1 as ink is withdrawn from the dipping well 6, the closure 4 is provided with an air conduit which communicates with the well 6 above the opening 7, when the container is reclining, the other end of the air conduit communicating with the interior of the container 1 above the level of the ink therein in either the reclining or upright position of the ink stand. Such air conduit, as shown, comprises a tube 21 having its lower end, Fig. 2, tightly secured in a hole 22 provided in the closure 4 above the opening 7, the tube 21 being extended from said hole 22 alongside the inner side of the closure wholly forward of the plane of the free end of the flange 5 of the closure. By reason of this construction, when the closure is removed from the container 1 and laid on the flange 5, the tube 21 will be in a position in which it will be protected from injury, and will also have its upper end positioned so as to permit of a maximum

amount of ink in the container 1 without the ink overflowing into the upper end of the tube 21, when the container is reclining.

To fill the container 1 with ink, the lever arms 16 of the lever are swung from the position shown in solid lines in Fig. 2 to the position shown in dotted lines in said figure, thereby through the eyes 15 moving the U shaped clamping member from the clamping position and freeing the closure 4, which can then be removed. After filling the container, the closure 4 is replaced and the lever arms 16 and clamping member are swung back to the clamping position, shown in solid lines in the three Figures 1, 2 and 3. In swinging to this position, the arms of the clamping member 13 pass the inwardly turned ends of the arms 16 and the arcuate portion 20 strikes the container 1, thereby reliably holding the closure 4 in the tightly closed position.

When the inkstand is to be used, it is placed in the reclining position, shown in Fig. 1, upon which the ink will flow from the container 1 through the opening 7 into the dipping well 6 until the level of the ink in the well rises above the lower end of the air conduit tube 21, which when thus closed will prevent air entering the container until sufficient ink has been withdrawn from the well to uncover the lower end of the tube 21, at which time air will pass upwardly through the tube 21 into the container 1 until the ink again covers the lower end of the tube in the well 6.

Due to the inclining of the container 1, when reclining, all of the ink therein can be used therefrom, as the bottom of the well is lower than the lower side of the container.

After being used, the ink stand is disposed in the upright position upon which the closure 11 will automatically close, and the ink in the well 6 will run through the opening 7 back into the container 1, thus preventing the accumulation of sediment in the well and always affording a fresh supply of ink thereto.

In the form shown in Figs. 4 and 5, the container body 23 is cylindrical, although it may be of other shapes, and is provided with an outwardly flaring ink chamber 24. The open end of the body 23 is circular and threaded externally and has fitted on it a gasket 25 against which is adapted to bear an annular flange 26 of a closure 27, the flange being threaded internally and removably fitting the threaded end of the container body 23.

The closure 27 otherwise conforms to the closure 4 being provided with the opening 7 connecting the well 6 with the container chamber 24. The well 6 has a sloping bottom, when the ink stand is reclining, as shown, and the lower side of the chamber 24 is on the inclined plane of the bottom 130

of the well, so that all of the ink in the chamber 24 can eventually flow into the well.

The top of the well 6 is closed and provided with the bushing 8, corresponding to the bushing 8 of the first described form, the bushing having pivoted to it a closure 11 adapted, as in the other form of my invention to automatically close when the ink stand is disposed upright with the closure 27 at the top. The closure 27 is also provided with an air tube conduit 21 disposed in the closure 27 in the same manner as has been described with reference to the form shown in Fig. 1. As shown in Figs. 1 and 15 4, the end of the tube 21, which is in the ink container, upwardly tapers, which prevents the forming of a drop of ink at this end of the tube when ink flows through the tube 21 from the dripping well 6 into the container, when the ink stand is turned from the reclining to the upright position.

In the form shown in Figs. 4 and 5, to fill the container 23 it is but necessary to unscrew therefrom the closure 27.

25. When the closure 27 is screwed onto the container, the screw threads hold the closure tightly against the container.

As in the other form of my invention when the container 27 is reclining, as shown in Fig. 30 4, the ink will flow into the well 6 until its level therein covers the lower end of the air tube 21, and this level will be maintained until the level of the ink in the container 23 lowers to the height of the opening in the 35 lower end of the tube 21.

In order to keep the ink stand in proper position when reclining, the closure 27, as shown in Fig. 5, is provided with two peripheral lugs 28 at opposite sides respectively of the dipping well 6, which lugs are adapted to rest on the surface of the support for the ink stand.

I do not limit my invention to the structures shown and described, as modifications other than shown may be made, within the scope of the appended claims, without departing from the spirit of my invention.

What I claim is:—

1. In an ink stand, an ink container having a discharge opening, a removable closure for said opening having a dipping well adapted to receive a pen and communicating with said opening and disposed, when said container is in operative position, in a position 50 in which the ink will flow by gravity through said opening into said well, and clamping means connecting said container with said closure adapted to hold the latter releasably clamped against said container, 55 and in the clamping position serving to support the container in the operative position.

2. In an ink stand, an ink container having a discharge opening, a removable closure for said opening having a dipping well adapted to receive a pen and communicating with

said opening and disposed, when said container is in operative position, in a position in which the ink will flow by gravity through said opening into said well, a clamping member engaging said closure and movable to and from a position in which it will releasably hold said closure tightly pressed against said container, and means engaging said clamping member adapted to move said member to and hold it in the clamping position and serving as a support for holding said container in the operative position.

3. An ink stand having a dipping well provided with an opening adapted to receive a pen, the ink stand having a chamber communicating with said well and adapted to contain a supply of ink, said ink stand being adapted to be moved from an operative position, in which the ink will flow by gravity from said chamber into said well, to an inoperative position in which the ink in said well will flow therefrom into said chamber, a closure for said opening, and means connecting said closure with said ink stand by which when the closure is in the open position and the ink stand is moved from the operative position to the inoperative position, said closure will be moved by gravity to a position closing said opening.

4. An ink stand having a dipping well provided with an opening adapted to receive a pen, the ink stand having a chamber communicating with said well and adapted to contain a supply of ink, said ink stand being adapted to be moved from an operative position, in which the ink will flow by gravity from said chamber into said well, to an inoperative position in which the ink in said well will flow therefrom into said chamber, a closure for said opening, and means pivotally connecting said closure with said ink stand by which when the closure is in the open position and the ink stand is moved from the operative to the inoperative position, said closure will swing by gravity to a position closing said opening.

5. An ink stand having an ink supply chamber and a dipping well having a pen receiving opening and communicating with said chamber and into which ink will flow from said chamber when the ink stand is in an inclined position, and from which the ink will flow into said chamber when the ink stand is in an upright position, said ink stand having means for holding it from revolving when in said inclined position, a closure for said opening, and means connecting said closure with said ink stand by which, when said closure is in the open position and the ink stand is moved from the inclined position to the upright position, said closure will be moved to the closed position.

6. An ink stand having an ink supply chamber provided with an opening, a removable closure for said opening communicating

through said opening with said chamber and having a dipping well into which the ink will flow from said chamber when the ink stand is inclined and from which the ink will flow 5 into said chamber when the ink stand is in an upright position, said closure having means for holding the ink stand from revolving when in said inclined position, a closure for said dipping well, and means connecting said 10 second named closure with said ink stand by which, when said second named closure is in the open position and the ink stand is moved from said inclined position to said upright position, said second named closure will be 15 moved by gravity to the closed position.

In testimony whereof I affix my signature.
ERNEST E. CLARK.
